Des. 196,879
Patented Nov. 12, 1963

196,879

PAIR OF WELDING GOGGLES

Donald T. O'Shea, Lakewood, Ohio, assignor to The Burdett Oxygen Company of Cleveland, Inc., Cleveland, Ohio, a corporation of Ohio

Filed Jan. 12, 1962, Ser. No. 68,292

Term of patent 3½ years

(Cl. D57—1)

FIG. 1 is a front elevational view of a pair of welding goggles, showing my new design;

FIG. 2 is a top plan view thereof; and

FIG. 3 is a side elevational view thereof.

The side not shown is substantially the same in appearance as the side shown.

I claim:

The ornamental design for a pair of welding goggles, substantially as shown and described.
